UNITED STATES PATENT OFFICE.

CLYDE W. KELLER AND LESTER H. CANNON, OF KANSAS CITY, MISSOURI.

INTERNAL-COMBUSTION ENGINE.

Application filed January 28, 1922. Serial No. 532,518.

To all whom it may concern:

Be it known that we, CLYDE W. KELLER and LESTER H. CANNON, citizens of the United States, residing at Kansas City, in 5 the county of Jackson and State of Missouri, have invented certain new and useful Improvements in Internal-Combustion Engines, of which the following is a specification, reference being had to the accompanying drawings.

This invention relates to internal combustion engines, and particularly to the valve mechanism thereof.

The general object of the invention is to 15 provide rotatable inlet and exhaust valves for internal combustion engines of a very simple character, and particularly to provide a cylinder head having valves mounted therein, and provide means whereby the exhaust valve and the inlet valve may be driven from the crank shaft of the engine.

A further object is to provide a cylinder head with rotary valves so mounted therein that the valves may be easily removed, and 25 provide an integral intake and exhaust manifold adapted to be detachably mounted upon the cylinder head and normally forming part thereof and extending the entire length of the valves.

30 A still further object is to provide improved means for keeping the valves cool and for oiling the valves and for preventing loss of compression and preventing the lubricating oil from getting into the cylinders of the engine.

Other objects have to do with the details of construction and arrangement of parts as will appear more fully hereinafter.

Our invention is illustrated in the accompanying drawings, wherein:—

Figure 1 is a longitudinal sectional view, with parts in side elevation, of an internal combustion engine embodying our invention;

45 Figure 2 is a vertical transverse section on the line 2—2 of Figure 1;

Figure 3 is a detail face view of the left hand end of the engine with the end cover plate removed;

50 Figure 4 is a detail sectional view of the valve casing;

Figure 5 is a detail sectional view illustrating particularly the springs for the valves;

55 Figure 6 is a detail view through one of the valves;

Figure 7 is a detail view illustrating one of the drainage troughs;

Referring to these drawings, it will be seen that we have illustrated a four-cycle 60 internal combustion engine of ordinary type having the usual cylinders 10, the usual crank case 11, the pistons 12, the crank shaft 13 operatively connected to the pistons, and the usual water jackets 14 surrounding the cylinders 10. The pistons 12 are of ordinary construction and all the parts which have been referred to are of conventional form.

Mounted upon the upper end of the piston block and constituting the cylinder head for 70 the block is a casting 15, this casting being formed to provide two longitudinally extending, cylindrical valve chambers 16. The inlet chamber has in its bottom a series of ports 17, the number of these ports corresponding to the number of cylinders in the engine, and the inlet chamber has in its top a number of ports 18 also corresponding to the number of cylinders. The exhaust chamber is provided with the ports 19 in 75 its bottom opening into the several cylinders and ports 20 in its top. Disposed upon the top of the casting 15 and either formed integral therewith or preferably bolted thereto is a casting 21 formed to provide two longitudinally extending chambers 22 and 23, the chamber 22 constituting an inlet manifold and the chamber 23 the exhaust manifold. Into these chambers the ports 18 and 20 open.

Extending longitudinally through the casting 15 are a series of intercommunicating water chambers 24 constituting means for keeping the valves in the chambers 16 cool. Disposed in the exhaust chamber is a tapered sleeve 25, and disposed within the inlet chamber is a tapered sleeve 26. Both of these sleeves are alike and, of course, the chambers 16 are also longitudinally tapered so that the sleeves will fit therein, this taper, however, being very slight. These sleeves 25 and 26 are removable from the chambers 16. Each of these sleeves is closed at one end by a screw-threaded annular cap 27 holding in place a tapered anti-friction bearing 28 having tapered anti-friction elements disposed in a suitable raceway. The forward ends of the sleeves 25 and 26 are closed by annular screw-threaded caps 29 holding in place the anti-friction bearing 30 105 having tapered anti-friction elements.

Disposed within the sleeve 25 is the ex-

haust valve 31. This is a solid shaft having reduced ends 32 and 33 adapted to be disposed within the bearings 28 and 30 and rotate therein, this shaft-like valve having 5 a plurality of diametrically extending ports 34 formed therethrough, these ports being separated from each other by circumferential grooves 35 wherein resilient packing rings 36 are disposed, these packing rings 10 15 expanding against the interior of the sleeve 25 and preventing communication between the cylinders and loss of compression. The extremity 32 of the valve 31 is reduced, as before stated, and then tapered, this tapered 20 end being formed with a keyway. Carried upon this tapered end is the gear wheel 37 held in place by a suitable key and gear nut 38 engaging the extremity of the shaft. The inlet valve 39 is of the same character as the 25 exhaust valve 31 and is formed with the diametrically extending passages or ports 40. This inlet valve has one end reduced to fit within the bearing 28 and the other end reduced to fit within the bearing 30, this reduced 30 end being formed with a keyway and held upon this reduced end is the gear wheel 41 which meshes with the gear wheel 37.

Mounted upon the wall 42 of a housing 43 is a shaft 44 carrying a gear wheel 45 which 35 meshes with the gear wheel 37 and also carrying upon it the sprocket wheel 46, over which a sprocket chain 47 passes. This sprocket chain passes around a sprocket wheel 48 mounted upon the crank shaft 13. 40 The sprocket chain is of the silent type and the ratio of the gears is such that the valves are driven at one-fourth of crank shaft speed.

The sleeves 25 and 26 are each formed 45 with diametrically disposed ports 49 coinciding with the ports 17, 18, 19 and 20 respectively and the bottom of the sleeve on each side of the lower series of ports 49 is formed a plurality of longitudinally extending slots 50, each pair of slots on each side of the ports 49 being relatively deeper than and being longer than the corresponding port 49. The casting 15 is formed on each side of the 55 port openings 17 and 19 with longitudinally extending recesses 51 in which are disposed oil scrapers 52, these oil scrapers being resilient, metallic strips slightly curved to conform to the curvature of the rotating valve and resiliently urged by springs 53 into contact with the respective valves. These scrapers act to prevent oil passing into the ports 17 and 19 from the rotating valves and act to prevent any loss of compression. The 60 inlet valve 39 rotates in a clockwise direction and the exhaust valve 31 in a counter-clockwise direction.

Formed in the casting 15 between the valves and adjacent the bottom of the casting is a longitudinally extending trough 54 which at its sides opens to the chamber 16

adjacent the scrapers 52 so that oil which may be scraped from the valves 31 and 39 will pass into this drainage trough 54. This drainage trough extends the entire length of the machine and is connected to the 70 crank case by a suitable duct so that the excess oil from the valves will pass down into the crank case. Outward of the outer scrapers 52 the casting 15 is formed with longitudinally extending oil ducts 55 whereby oil is applied to the valve, it being understood that the sleeves 25 and 26 are formed with openings permitting the oil to pass to the exterior of the valves and be scraped off of the exterior of the valves. compression. By removing the valves and the sleeves, the oil scrapers may be readily removed from their recesses for the replacement of springs or the replacement of the scrapers themselves. Our construction provides a valve in the head engine of such construction that the valves are not liable to get overheated and bind, and of such construction that the valves may be readily timed.

While we have illustrated certain structural details and a certain arrangement of parts which we believe to be particularly effective, we do not wish to be limited there-
to as it is obvious that many changes might be made in these details and in the exact arrangement of the parts without departing from the spirit of the invention as defined in the appended claims.

20 We claim:—

1. An internal combustion engine includ-
ing an engine block, a cylinder head, two
parallel, longitudinally extending chambers
formed with ports opening into the cylin-
ders, parallel, contiguous inlet and exhaust
manifolds extending longitudinally from the
chambers and having ports opening there-
into, two parallel, solid valves disposed in
said chambers and rotating therein and each
having diametrically extending ports equal
in number to the number of the cylinders,
engine operated means for rotating said
valves, means for supplying oil to the valves,
means for preventing the passage of oil into
the cylinders comprising spring actuated
strips disposed in the cylinder head on each
side of the ports leading to the cylinder and
yieldingly bearing against the rotatable
valves, there being a pair of said strips as-
sociated with each port in each valve and
being disposed on each side of each port,
said strips being convergent with relation
to each other and the port, a drainage cham-
ber opening through the walls of the valve
chambers inward of the contiguous strips
whereby to receive surplus oil from said
valves, and means for conducting the oil into
said drainage chamber to the crank case of
the engine.

50 2. An internal combustion engine includ-
ing an engine block, a cylinder head having
a longitudinally extending valve chamber
having diametrically disposed ports, one se-
ries of ports opening into the cylinder, a
manifold into which the other series of ports
open, a sleeve disposed within the chamber
and removable therefrom and having ports
registering with the ports of the chamber,
the chamber having recesses in its walls dis-
posed on each side of the ports leading to the
cylinders, a sleeve having slots registering
with said recesses, strips disposed in said
slots and recesses, springs urging the strips
inward, a rotatable valve disposed in the
chamber and having diametrically extend-

ing ports adapted to establish or cut off com-
munication between the manifold and the
cylinder as the valve rotates, said strips
bearing against the periphery of the valve,
said valve between its ports having circum-
ferentially extending grooves, packing rings
disposed within said grooves, means for sup-
plying lubricant between the exterior of the
valve and the sleeve, and means disposed
adjacent one set of said strips for withdraw-
ing excess lubricant.

3. An internal combustion engine includ-
ing an engine block, a cylinder head having
two parallel, longitudinally extending
chambers formed with a series of ports open-
ing into the cylinders, a series of diametri-
cally disposed ports, the cylinder head being
formed with water passages extending lon-
gitudinally of the cylinder head and con-
tiguous to said chamber, a casting detach-
ably engaged with the cylinder head and
disposed above the same and having two
parallel, contiguous, longitudinally extend-
ing intake and exhaust manifolds into which
the ports of the cylinder head open, sleeves
disposed within said chambers and forming
a lining for the same and having ports regis-
tering with the ports of the chambers, the
wall of the chamber being provided with a
series of longitudinally extending recesses
on each side of the several ports opening
into the cylinders, and the sleeve having cor-
responding slots, scrapers disposed in said
recesses and slots and resiliently urged in-
ward, the walls of the chambers and the
sleeve being formed with longitudinally ex-
tending oil connecting ports opening into
the interior of the sleeves inward of the con-
tiguous strips of the two cylinders, an oil
drainage chamber into which said ports
lead, longitudinally extending rotatable
valves disposed in said sleeves and having
each a series of diametrically extending
ports adapted to align with the ports of the
sleeve chambers, engine operated means for
rotating said valves in opposite directions,
and means for supplying oil to the space be-
tween the valves and corresponding sleeve.

4. An internal combustion engine includ-
ing an engine block, a cylinder head having
two parallel, longitudinally extending cham-
bers formed with a series of ports opening
into the cylinders, a series of diametri-
cally disposed ports, the cylinder head being
formed with water passages extending lon-
gitudinally of the cylinder head and con-
tiguous to said chamber, a casting detach-
ably engaged with the cylinder head and
disposed above the same and having two
parallel, contiguous, longitudinally extend-
ing intake and exhaust manifolds into which
the ports of the cylinder head open, sleeves
disposed within said chambers and form-
ing a lining for the same and having ports
registering with the ports of the chambers,

the wall of the chamber being provided with a series of longitudinally extending recesses on each side of the several ports opening into the cylinders and the sleeve having corresponding slots, scrapers disposed in said recesses and slots and resiliently urged inward, the walls of the chambers and the sleeve being formed with longitudinally extending oil connecting ports opening into the interior of the sleeves inward of the contiguous strips of the two cylinders, an oil drainage chamber into which said ports lead, longitudinally extending rotatable valves disposed in said sleeves and having each a series of diametrically extending ports adapted to align with the ports of the sleeve chambers, each of said valves being reduced at its forward and rear ends, anti-friction bearings carried in the sleeve through which said reduced ends pass, caps having screw-threaded engagement with the sleeves and holding the bearings in place, engine operated means for rotating said valves in opposite directions, and means for supplying oil to the space between the valves and corresponding sleeve.

In testimony whereof we hereunto affix our signatures.

CLYDE W. KELLER.
LESTER H. CANNON.
